UNITED STATES PATENT OFFICE.

GEORGE W. OTTERSON, OF SEATTLE, WASHINGTON, ASSIGNOR TO THE OTTERSON AUTO-EDUCTOR CO., OF SPRINGFIELD, OHIO, A CORPORATION OF WASHINGTON.

APPARATUS FOR CLEANING CATCH BASINS AND THE LIKE.

Application filed June 19, 1919. Serial No. 305,239.

To all whom it may concern:

Be it known that I, GEORGE W. OTTERSON, a citizen of the United States, and resident of Seattle, in the county of King and State 5 of Washington, have invented a new and useful Apparatus for Cleaning Catch Basins and the like, of which the following is a specification.

The invention relates to traveling apparatus 10 for cleaning catch-basins and the like, such as that disclosed in my Reissue Patent No. 14,234, Dec. 19, 1916. The object of the present invention is to provide a simplified form of the vehicle tank-body settling-bed forming a part of such apparatus. 15 Previously the baffle partitions were disposed transversely of the tiltable rear-dumping tank and were hung swingingly so that the separated solids could pass out 20 beneath them. In the present instance the baffles are placed longitudinally so as to form lengthwise settling chambers from which the material can escape in dumping without movement of the partitions; at the 25 same time the organization is such that a circuitous flow is compelled from the inlet from the discharge line to the outlet to the pump which operates the ejector.

In the drawings forming a part hereof:

30 Fig. 1 is a side elevation of an apparatus embodying the invention, the settling-bed being shown partly in side elevation and partly in section, and broken lines being used to show it partly tilted; and

35 Fig. 2 is a plan view.

The motor-vehicle 1 has a rectangular tank-body 2, its interior open to the pressure of the atmosphere, a pump 3 adapted to be driven from the engine of the vehicle 40 by connections, not shown, and a hydraulic ejector 4 connected with the outlet of the pump and adapted to draw in and raise the contents of the catch-basins and cause their delivery into the settling-bed. The 45 ejector 4 is adapted to be lowered into and raised from the basins, and has a suitable flexible pressure line 5 forming the connection between the outlet of the pump and the ejector-jet nozzle (not shown), and a 50 flexible or telescopic discharge line 6 terminating in a suitable nozzle 7 projecting over the top of the settling-bed. An inlet line to the pump is marked 8, the same leading from a clear-water outlet 9 at one of

the lower forward corner regions of the 55 settling-bed. A separable, automatically making and breaking connection 10 between said outlet and the inlet end of the line 8 is provided as disclosed in prior applications. The nozzle 7 of the discharge line is 60 adapted to deliver the mixed stream of water and solids into the other forward corner region of the tank. In such an apparatus, with the tank in normal position, the 65 ejector let down into a basin and the pump in operation, water is withdrawn from the settling-bed, wherein a supply is kept while the machine is upon its rounds, forced by the pump downward to the ejector, where the ejector jet is created, drawing in the 70 contents of the basin through the intake 11 and forcing them upward to the settling bed on the vehicle, where the liquid is separated from the solids and continuously used to supply the pump and jet. When the 75 cleaning is completed, excess water is run back into the basin through a line 12.

The tank body is pivoted toward the rear upon the vehicle frame, as indicated at 13, and suitable hoisting means 14 is provided 80 for raising its forward end in order to discharge the accumulated material at the back. A tight tail-gate 15 hinged at the top is unfastened and swings rearward in this operation.

85 The interior of the tank contains a plurality of vertical baffles 16, 16^a, 16^b interrupting the flow of the water from the inlet from the discharge line to the clear-water outlet 9, causing it to pass in a circuitous 90 manner so that the two regions are remote in point of flow. The number of these partitions may be varied, but it is characteristic of the present improvements that they extend longitudinally of the settling-bed, 95 that is to say, fore and aft of the vehicle, and are or may be fixed. Flow openings 17, 17^a, 17^b are formed in their upper parts, alternately at front and rear, the baffle 16 nearest the inlet from the discharge line 100 having its opening at the rear, and the opening in the last partition being likewise at the rear. In this way a circuitous flow is compelled, as indicated by the arrows, through a series of lengthwise settling-chambers 18, 18^a, 18^b, and a clear-water passage 19. The chute-like settling-chambers are entirely 105 open at the rear when the tail-gate swings

outward and consequently their solids pass out freely when the tank is tilted for dumping.

What I claim as new is:

- 5 1. In traveling apparatus for cleaning catch-basins and the like, a settling-bed comprising a vehicle tank-body tiltable for rear dumping and having longitudinal baffles forming lengthwise settling-chambers.
- 10 2. In traveling apparatus for cleaning catch-basins and the like, a settling-bed comprising a rear-dumping vehicle tank-body divided into lengthwise communicating settling-chambers, with flow openings alternately at front and rear of the baffles.
- 15 3. A settling bed comprising a tank-body tiltably mounted on a vehicle for rear dumping and having a tight tail-gate, and equipped with longitudinal partition means
- 20 provided with flow openings and dividing

the interior into lengthwise unobstructed settling chambers whereby the solids are retained and are freely discharged through the tail-gate opening when the settling-bed is tilted on its support.

25

4. A traveling apparatus for cleaning catch-basins and the like, comprising a vehicle, a tiltable rear-dumping tank-body thereon, a pump having a clear-water inlet connection from the tank, a hydraulic ejector connected with the outlet of the pump and a discharge line for delivering back into the tank, characterized by longitudinal baffles in the tank forming a series of lengthwise compartments with circuitous communication, the outlet to the pump and the inlet from the discharge line being in laterally remote compartments.
